UNITED STATES PATENT OFFICE.

GEORGE W. BARIAN, OF FOWLERVILLE, MICHIGAN.

MACHINE FOR GRINDING HORSESHOE-CALKS.

SPECIFICATION forming part of Letters Patent No. 417,582, dated December 17, 1889.

Application filed July 13, 1889. Serial No. 317,491. (No model.)

To all whom it may concern:

Be it known that I, GEORGE W. BARIAN, a citizen of the United States, residing at Fowlerville, in the county of Livingston and State 5 of Michigan, have invented certain new and useful Improvements in Machines for Grinding Horseshoe-Calks, of which the following is a specification, reference being had therein to the accompanying drawings.

This invention relates to new and useful improvements in machines for sharpening horseshoe-calks.

The invention consists in the peculiar construction of a machine having a grinding-wheel and mechanism to drive the same adapted to be attached to a horseshoe while upon the foot of a horse, and means for tilting the machine to place the grinding-wheel at the desired angle to the calk; further, in the peculiar construction of the device for feeding the grinding-wheel to its work; further, in the peculiar construction of the clamp attached to the horseshoe and of the clamp for securing the frame of the machine to the shoe-clamp, and, further, in the construction, arrangement, and combination of the various parts, all as more fully hereinafter described.

In the drawings which accompany this specification, Figure 1 is a perspective view of my improved machine as in use with some of the parts detached. Fig. 2 is a side elevation thereof. Fig. 3 is an end elevation thereof, looking toward the grinding-wheel, which is shown in dotted lines. Fig. 4 is a cross-section on line $x-x$ in Fig. 2. Fig. 5 is a vertical central section, partly in elevation, of the shoe-clamp and frame-clamp. Fig. 6 is a plan of the shoe-clamp. Fig. 7 is a top plan of the frame-clamp. Fig. 8 is a section thereof on line $z-z$ in Fig. 7.

A is a rectangular frame, having a detachable top or cap A', secured by bolts or rivets a. The sides of this frame have the slots B, preferably extending the entire length of the frame, and in these slots are secured the sliding bars B', having suitable side grooves b, engaging into the sides of the slots B. The upper ends of these bars are cut away to 45 form the bolts c, which pass through the cap and are provided at their upper end with suitable screw-threads to receive a nut c', by

which the bars may be adjusted up or down, springs d being sleeved over the bolt below the cap, bearing with their lower end against 55 the shoulders d' on the bars. The shaft C is journaled in the upper end of these bars, carrying at one end the gear-wheel C', having the handle C², and at the other end the handle C³. This wheel meshes with the sliding 60 pinion D, secured upon the shaft D', which is journaled in the lower ends of the bars B', carrying at the other end the grinding-wheel, preferably an emery-wheel. The pinion D has a sufficiently wide periphery to admit of 65 its being kept in engagement with the gear-wheel in any of its adjusted positions.

E is a collar secured upon the shaft D', having the groove e, in which the lever f engages, this lever being fulcrumed in one of 70 the notches g in the cross-bars g' of the frame, and adapted to move the shaft with the grinding-wheels acting against the spring g'', sleeved upon the shaft.

E' is a tilting-foot pivotally connected to 75 the base of the frame by the bolt g³ at one side, and at its free end provided with the upwardly-extending arm h, which may be vertically adjusted by the screw-threaded bolt h', having the crank-handle h². The bolt 80 h' is supported in the bearing h³ in the cap, and the arm h is held from lateral displacement by the set-screw i engaging in the slot i' in the frame.

F is the shoe-clamp, having the rack-bar F', 85 provided with the slot F² and the clamping-jaws G G'. The clamping-jaw G is pivotally connected to the stationary pin j, while the jaw G' is secured to the sliding pin j', which is pivotally secured to the slide j².

H is a sliding spring-catch, having the pin k, carrying the cross-bar k', which is held in contact with the teeth of the rack-bar by the spring k'' in the casing k³. The arm l of the casing carries the cam l', having a suitable 95 handle l''. The spring-catch being in suitable proximity to the jaw G' when engaged upon the shoe of the horse, as shown in Fig. 1, allows of tightly clamping it thereon by turning the cam-lever to bear against the 100 jaw G'.

The frame of the machine is secured to the shoe-clamp by means of the bolt I, which is slidingly secured in the slot F'' of the rack-

bar by means of the groove m , and passes upward through the frame of the machine through the slots $m' m^2 m^3$ in the hinge-piece, the bottom, and top, respectively, of the frame. 5. The bolt is provided at the top with a clamping device J , for clamping the machine-frame firmly to the shoe-clamp.

Of the following description, o is the clamp-plate, having a suitable aperture for the bolt, 10 and a slotted extension o' , in which the body of spring-catch o^2 is engaged by means of the set-screw p engaging in the slot. p' is the spring-dog, having suitable teeth to engage into the upper rack-bar on end of the bolt I . 15 q is a double cam pivoted to the body of the spring-catch, and provided with the handle q' , all so arranged that by turning the handle q' into a vertical position, as shown in Fig. 2, the dog being engaged with the bolt, the 20 cams bear down upon the plate o and lift the bolt I , thereby firmly clamping the frame to the shoe-clamp.

The parts being thus constructed and arranged, they are intended to operate as follows: 25 The operator clamps the device upon the horse's shoe, as shown in Fig. 1, by means of the shoe-clamp, the jaws G and G' bearing upon each side of the shoe and being held tightly in position by means of the cam-levers l'' . 30 The clamping device at the top of the bolt I being loose, it is evident that the frame of the machine is free to turn in any direction, being pivoted upon the bolt I . The operator adjusts the frame of the grinding-wheel in 35 proximity to the calk which he desires to sharpen, tilting the frame by means of the tilting-foot E' , moving it up or down by turning the crank h'' until the grinding-wheel assumes the angle at which he desires to 40 sharpen the calk. Then by pressing downward upon the handle of the spring-catch o'' he adjusts the catch to the desired point to allow of bringing the double cam q into operation, turning it into the vertical position, as shown 45 in Fig. 2, thereby clamping the frame in its adjusted position firmly to the shoe-clamp. The operator then revolves the gear-wheel C' with one hand and with the other presses upon the outer end of the lever f , which is 50 fulcrumed in the notch g , as before described, thus feeding the grinding-wheel up against the calk to the desired degree, the side of the grinding-wheel grinding the side of the calk, the operation being continued until the desired object is accomplished. Should the wheel in any way become caught or clogged 55 against the calk, the springs d will yield, and thereby prevent any damage to the wheel. When one calk is finished, by releasing the 60 cam q the frame may be turned around to operate upon the other calks of the shoe without detaching it, and may be slid along and adjusted in the desired relation to such

calk, again clamped in position, and the operation repeated. The pinion D is made with 65 a periphery of sufficient width to allow of feeding the shaft D' , on which the pinion and the grinding-wheel are journaled, backward and forward without becoming disengaged from the gear-wheel C' . When the 70 operation is completed, the operator has simply to turn the cam-lever L'' , thereby loosening the clamp from the foot, and the whole machine may be at once taken off. In case 75 the horse becomes unruly the operator can thus detach the machine without delay, so that there is no danger of its becoming damaged or of injury to the horse.

What I claim as my invention is—

1. In a machine for grinding horseshoe-calks, a shoe-clamp consisting of jaws secured to a slotted rack-bar, a grinding-frame pivotally secured thereto by means of a clamping-bolt slidingly engaging in the slot of the rack-bar, and means, such as the tilting-foot E' , for tilting the frame, substantially as described.

2. In a machine for grinding horseshoe-calks, the combination of the frame carrying the grinding devices, the foot pivoted to said frame, the rod connected to the free end of said foot, and the screw carried by the frame and engaging said rod for tilting the frame, substantially as described.

3. In a machine for grinding horseshoe-calks, a shoe-clamp, a frame carrying a grinding device secured thereto by means of a bolt, a clamping device at the upper end of said bolt, consisting of the slotted clamping-plate o , the spring-catch o^2 , and spring-dog p' , adapted to engage with the rack-bar on the bolt, and the cam-lever q' , substantially as described.

4. In a machine for grinding horseshoe-calks, the combination of the frame having the slotted sides, the bars adjustable in said sides, the shaft carrying the driving-gear, the shaft carrying the grinding-wheel and sliding pinion, the lever for moving the shaft, and the notched bar for retaining the lever in the proper position, substantially as described.

5. In a machine for grinding horseshoe-calks, the combination of the frame, the shaft carrying the grinding-wheel mounted therein, the collar on said shaft, the shifting lever engaging said collar, and the notched bar for retaining the lever, substantially as described.

In testimony whereof I affix my signature, in presence of two witnesses, this 22d day of May, 1889.

GEORGE W. BARIAN.
